UNITED STATES PATENT OFFICE.

GEORGE B. THORPE, OF CHICAGO, ILLINOIS.

ROLLER WINDOW-SCREEN.

1,091,095.

Specification of Letters Patent. Patented Mar. 24, 1914.

Application filed September 7, 1912. Serial No. 719,084.

To all whom it may concern:

Be it known that I, GEORGE B. THORPE, a citizen of the United States, residing at Chicago, county of Cook, and State of Illinois, have invented new and useful Improvements in Roller Window-Screens; and I do hereby declare the following to be a full, clear, and exact description of my invention, such as will enable others skilled in the art to which it appertains to make and use the same, reference being had to the accompanying drawings, and to the references marked thereon, which form part of this specification.

This invention relates to new, useful and novel improvements in roller screens for windows.

The object of the invention is to produce a simple, and efficient device of this kind, comprising a spring actuated roller, upon which a screen is adapted to wind secured to the jambs of a window frame, and so adjusted that the entire opening of the window is covered by the screen, thereby permitting the adjusting of both the upper and the lower sash of window as desired.

My invention consists, further, in various other details of construction, combinations, and arrangements of the parts, which will be hereinafter fully described, and then specifically defined in the appended claims.

I hereby illustrate my invention in the accompanying drawings, in which:—

Figure 1 is a left hand, side, sectional view of a window frame, showing attachment of the cap, the screen and the roller thereto. Fig. 2 is a top view of a spring roller looking downward. Fig. 3 is a detail view of a combined spring and bolt. Fig. 4 is a detail front elevation and perspective view of a bracket which holds the stationary pintle. Fig. 5 is a combined view of a roller Fig. 2 and the bracket Fig. 4 showing them attached, with part cut away on the line B and B of the roller, Fig. 2 and on the line A and A of the bracket. Fig. 6 is a perspective top view of the bracket which holds the revolving pintle of the roller Fig. 2. Fig. 7 is a face view of a pintle as attached to the end of a roller (Fig. 2) showing the bolt and opening through the pintle with the pawl dislodged from the opening in the top of the pintle by a bolt. Fig. 8 is a top perspective view of a cap showing the hangers by which it is attached to a window frame.

The object of my improvement is to secure a cheap, practical window screen, which

the above description and illustrations show; therefore I have adopted a screen, which works on the principle of the spring-roller window shade; now in universal use.

My improved roller is adjustable, in so much that it can be converted from a pawl controlled spring actuated eccentric roller, into a free spring actuated roller, this is accomplished by the spring actuated roller having pintles on the ends, one of said pintles having an opening therethrough in which the pawls engage to prevent the roller revolving; and through which a bolt ascends dislodging the pawls thereby permitting the roller to revolve freely.

For manufacturing, I prefer the combined bolt 6' and spring 6 shown in Fig. 3. The pintle 11 when placed in the opening 10 rests on the seat 3, of the bracket Fig. 4 with the edge coming into contact with the spring 6 of the bolt 6' at a sufficient distance from the end of the pintle where the spring 6 is secured by a rivet at 7, causing the bolt 6' to ascend and fill the opening 2 in the pintle, thereby disengaging or forcing the pawls therefrom. The pawls 5 come into use when adjusting the pintle in the bracket, or when removing the roller 1 from the bracket, as is sometimes necessary when the tension is not strong enough, or other repairs required, and this is done automatically by raising the roller 1 from the bracket Fig. 4, the spring bolt 6' having the spring 6, which is secured by a rivet at 7 to the under side of the pintle 11, springs down, leaving the hole 2 in the top of the pintle 11 open which the pawls enter—thereby preventing the roller 1 from revolving.

To strengthen the tension of the spring 95 in the roller, when required, pull the screen down a foot or two—remove the roller 1 from the brackets—roll up the screen on the roller and replace the roller in the brackets. The pawls 5 are very essential to 100 the working of the device. Without them it would be almost impossible to control the recoil of the spring inside of the roller 1 when removed from the brackets.

The brackets should be made of metal, and 105 the openings 10 and 14, shown in Fig. 4 and Fig. 6, cut out to receive and hold the pintles 11 and 12, and the edge of the metal bent back so as to form a ledge of sufficient depth to keep the face of the bracket at a 110 proper distance from the jamb or lining of the window frame, to which the bracket is

attached by the screws 4 so as to prevent the end of the pintle coming into contact with the jamb or lining of the frame. The brackets should be made by the metal stamping process out of one piece of metal. The cap Fig. 8 can be made of wood or metal and should be fitted close to top of the window, so as to prevent the entrance of insects into the apartment, and is suspended by the hangers 16, fastened by screws so as to hang down on an angle with the lower edge resting on or against the screen cloth 17, which is rolled upon the roller 1 which it will follow downward by gravity and is raised by the increasing pressure of the bulk of the roller as the screen is wound upon the roller by the raising of the screen in the window. The screen cloth 17 should be secured by wire bands surrounding the roller which are secured to the roller by tacks or otherwise, with the stationary pintle 11 to the left hand side, the revolving pintle 12 to the right. Of course, this arrangement could be reversed where there is sufficient space on the jambs of a window to permit the screen working freely inside the sash of a window, or the screen could be attached to the outside of the frame of a window with the sash inside if desired, by protecting it with a shelter cap. At the bottom is a cross bar 18 which should be the same length as the opening between the guide tubes on both sides of the window. The weight of the cross bar 18 should be adjusted to counteract the tension of the spring in the roller 1 thereby holding the screen taut and where it is desired for it to stay, as it is raised or lowered in the window. The screen cloth 17 is secured at the bottom between the bar 18 and the strip 15 by rivets, and the strip 15 should be the same length as the width of the screen cloth 17. The ends of the strip 15 should be flanged to engage with the guide in which it slides. This device should be attached to a window as follows: By securing the bracket Fig. 4 with screws 4 to the left hand side of the window, and the bracket 14 to the right hand side with a screen guide on each side of the window, and the follower cap 13 secured to the top of the window frame or jamb lining by the hangers 16 with screws, the screen cloth being wound upon the roller with tension properly adjusted. Place the revolving pintle 12 in the hole 14 of the brackets and adjust the other pintle 11 in the opening 10 with the spring 6 which is secured to the bottom of pintle 11, resting on the seat 3 of the opening 10 in bracket Fig. 4. Then place the screen, which is secured to the metal strip 15, into the slot in the top of the screen guides on each side of the window, pull down the screen to the sill of the window, see that it works easily up and down in the window. The friction

of cross strip and screen in the guides and the weight of the cross bar 18, if properly adjusted, will offset the strength of the spring in the roller 1 and cause the screen to stay where placed. For convenience in handling, when raising or lowering the screen, handles 25 should be secured to the bar 18 about 4 inches from either end. 70

What I claim and desire to secure by Letters Patent is:

1. A window screen comprising cloth attached to a spring actuated roller, having a revolving pintle on one end and on the reverse end a stationary pintle having automatic working pawls, a spring bolt to control the action of the pawls; a follower cap suspended by hangers to the top of a window frame, with the lower side resting on the screen and adjusted to automatically follow by gravity the diminished bulk of the screen on the roller and raised by pressure of the increasing bulk on the roller caused by the raising of the screen in the window; a weight attached to the bottom of the screen which counteracts the tension of the spring in the roller; substantially as set forth. 75

2. The combination of a window screen with a spring actuated roller, having automatic working pawls, which engage in an opening in the pintle and prevent the revolving of the roller; and a spring controlled bolt which, when the roller is placed in the brackets, ascends through the opening in the pintle, expelling the pawl therefrom; 95 and thereby permitting the roller to revolve freely; substantially as and for the purpose specified. 100

3. The combination of a screen with a spring actuated roller, the roller having a revolving pintle on one end and on the reverse end, a stationary pintle having an opening therethrough, said roller; having automatically working pawls, which engage in the opening in the pintle to prevent the spring roller revolving; a spring bolt, which ascends through the opening in the pintle, thereby disengaging the pawls and permitting the roller to revolve freely; a follower cap which is secured by hangers to the top of window frame, with the lower edge resting on the screen which is rolled upon the roller, and is by gravity and the increased or decreased bulk of the screen cloth wound on the roller, raised or lowered automatically following the screen and keeping the opening in the window above the roller closed; substantially as and for the purpose described. 110 115

4. The combination of a spring actuated roller with a screen attached thereto, said roller having self acting pawls and a pintle attached thereto, said pintle having an opening therethrough into which a bolt ascends, thereby preventing the pawls engaging in 120 125 130

said opening when the roller is revolving, a follower cap attached to the top of a window frame by hangers on one side, with the other side resting on the screen, wound on a 5 roller, and automatically raised or lowered by the winding of the screen on or off the roller; substantially as described.

5. The combination in a roller window screen, of a flexible screen cloth, with a 10 spring actuated convertible roller, having a revolving pintle on one end, on the reverse end self acting pawls and a stationary pintle, said stationary pintle having an opening therethrough in which the pawls engage and 15 prevent the roller revolving, and a bolt which ascends through the said opening, thereby dislodging the pawls and permitting the roller to revolve freely; substantially as and for the purpose specified.

6. A convertible spring actuated roller, 20 having a revolving pintle on one end; and on the reverse end a stationary pintle, said pintle having an opening therethrough, the said roller having automatically working pawls, which engage in the opening through 25 the stationary pintle, thus preventing the spring actuated roller revolving, and a bolt which ascends in the opening in the said pintle, dislodging the pawls, thereby permitting the roller to revolve freely; sub- 30 stantially as and for the purpose specified.

In testimony whereof I hereunto affix my signature in the presence of two witnesses.

GEORGE B. THORPE.
